W. C. MACKINNON.
PISTON RING REMOVER.
APPLICATION FILED JAN. 7, 1913.

1,071,934.

Patented Sept. 2, 1913.

UNITED STATES PATENT OFFICE.

WILLIAM C. MACKINNON, OF NEWARK, NEW JERSEY.

PISTON-RING REMOVER.

1,071,934.

Specification of Letters Patent.

Patented Sept. 2, 1913.

Application filed January 7, 1913. Serial No. 740,576.

To all whom it may concern:

Be it known that I, WILLIAM C. MACKINNON, a citizen of the United States, residing at Newark, in the county of Essex and State of New Jersey, have invented certain new and useful Improvements in Piston-Ring Removers; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to an improved piston ring holder which can be used for removing or installing piston rings in pistons, and is designed to facilitate said operation which is now slow and unsatisfactory on account of the difficulty to properly grasp and hold the ring in expanded position so that it will ride from its groove in the piston and can be withdrawn along the outside of the piston.

The invention provides for a holder for piston rings which spreads the ring by grasping it on its ends, the holder comprising handles which are recessed so as to receive the ends of the ring and which permit the ring being spread by reason of force being exerted at its ends at the split portion, but in a direction circumferential to the ring, that is, in a direction approximately longitudinal along the ring so that there is no tendency to bend the ends of the ring back without affecting the heavier part of the ring.

The invention is illustrated in the accompanying drawing, in which—

Figure 1 is a view of a piston ring with the holder in place, the holder in this instance consisting of separated members. Fig. 2 is an enlarged top view of the two members of the holder showing the ends of the piston ring when grasped. Fig. 3 is an enlarged detail of one of the members. Fig. 4 is a view of a different form of holder in which the members or handles are connected by a spring which has a normal tendency to force them apart. Fig. 5 is a diagrammatic view showing the direction of the lines of force directed against the ends of the split piston ring.

The holder consists of members which have suitable handles 10, preferably long

enough to be well grasped one in each hand, the handles having blocks 11 on their ends, which blocks are recessed so as to receive the ends of the split portion of the piston ring. The recess in each handle or holder is usually formed by forming a recess 12 in the block 11, the side walls 13 of the recess acting to limit the side movement of the piston ring 14, the recess on one end being open 60 so as to permit the handle being placed over the piston ring, the other end of the recess being closed by a projection, preferably in the shape of a pin 15. An overlapping portion 16, such as a head, prevents the recessed handle from slipping off the end of the ring. It will thus be seen that when a pair of these handles is placed in the split end of a piston ring as shown in Fig. 1, the ends 17 of the ring, which are usually bevelled, are engaged by the pins 15, and when the handles are swung apart circumferentially, that is, in the direction of arrows *a* in Fig. 5, the piston ring is spread to a diameter large enough to permit its being 70 withdrawn along the piston, and the same holders can be used for handling the piston ring and placing it in position in its groove in the piston. It will be noted that the direction in which these handles are used, that is, in the direction of arrows *a* in Fig. 5, forces the whole ring circumferentially so as to spread it and does not put a strain on the ends of the ring, in the direction of the arrows *b*, which strain would tend to simply 75 pull the ends of the ring outward and would not affect the whole ring to spread it.

In Fig. 4 is shown a remover which illustrates a manner of connecting the handles by means of a band 18 which encircles the piston ring and is preferably made of spring material and thus forms a means for normally forcing the handles and their blocks apart. The holding means in the blocks in this construction is similar to that shown in 80 Figs. 1, 2 and 3, but the manner of operation is slightly different inasmuch as the two handles are squeezed together with their adjacent edges meeting or nearly meeting, and this permits the pins 15 to be slid in the 85 open portion of the ring. Then by releasing the handles, the band 18, by its spring action which is in excess of the spring action of the piston ring, spreads the piston ring apart so that there is no labor employed in spreading 90 the piston ring, as that is done by the spring band 18. The band 18 can be made of

spring stock, or it can be cast and given a spring by the necessary peening.

In cases where the spring of the band 18 is excessive and its force might be too great for the piston ring, I provide means for limiting the movement of the handles away from each other, usually by a staple or loop 19.

It will be understood that details of construction can be changed without departing from the scope of my claims. It will be understood that all piston rings are not cut with the diagonal split portion as shown in the drawing, but it will be obvious, however, that with the different manners in which rings are cut, the pins can be disposed so as to enter between the open ends of the ring no matter what the shape of the cut is.

Having thus described my invention, what I claim is:—

1. A piston ring remover comprising a pair of handles, the handles having recesses in one end so as to embrace the two ends of a piston ring, and projections in the recesses, the projection on each handle being adjacent to the edge opposite the other handle, whereby the projections and the sides of the recesses are adapted to engage the ends of a piston ring.
2. A piston ring remover consisting of a pair of handles having recesses on their ends to receive the ends of a piston ring, pins in the recesses and adjacent to the meeting edges of the handles, the pins being adapted to engage the ends of the piston ring, and a spring connecting the handles and adapted to force them apart.

3. A piston ring remover consisting of a pair of handles having on their ends recesses to receive the ends of a piston ring, pins in the recesses and adjacent to the meeting edges of the handles, the pins being adapted to engage the ends of the piston ring, a spring connecting the handles and adapted to force them apart, and means for limiting the movement of the handles away from each other.

4. A piston ring remover consisting of a split spring, the spring being adapted to encircle a piston ring, the ends of the spring being separable, blocks on the ends of the spring, the blocks being recessed to receive the ends of the ring, pins in the blocks adjacent to their meeting edges, the pins being situated in the recesses, and handles for drawing the ends of the spring together.

5. A piston ring remover consisting of a split spring, the spring being adapted to encircle a piston ring, the ends of the spring being separable, blocks on the ends of the spring, the blocks being recessed to receive the ends of the ring, pins in the blocks adjacent to their meeting edges, the pins being situated in the recesses, handles for drawing the ends of the spring together, and means for limiting the movement of the handles from each other.

In testimony, that I claim the foregoing, I have hereunto set my hand this 3rd day of January, 1913.

WILLIAM C. MACKINNON.
